UNITED STATES PATENT OFFICE.

THOMAS ALLSOP AND WALTER W. SIBSON, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

DRYING-MACHINE.

No. 901,769.

Specification of Letters Patent.

Patented Oct. 20, 1908.

Application filed September 25, 1907. Serial No. 394,480.

To all whom it may concern:

Be it known that we, THOMAS ALLSOP and WALTER W. SIBSON, citizens of the United States, residing at Philadelphia, in the 5 county of Philadelphia and State of Pennsylvania, have invented certain new and useful Improvements in Drying-Machines; and we do hereby declare the following to be a full, clear, and exact description of the invention, such as will enable others skilled in 10 the art to which it appertains to make and use the same.

This invention relates to improvements in drying machines, and more particularly has 15 reference to machines for drying bathing suits.

The present invention primarily has for its object the provision of a machine that is automatic in its operation, whereby the bathing 20 suits after being introduced to the machine will traverse the drying chamber and return to the feed end of the machine, at which point the suits will be automatically discharged from the machine, thus dispensing 25 with manual labor for effecting such discharge, and reducing to a minimum the number of attendants for as well as the expense of operating the machine.

A further object of the present invention is 30 to provide a machine of the character stated the construction of which is such that its operation may be accomplished with the greatest economy in the use of the heating medium employed, and by which the suits, at 35 the initial stage of transit through the machine, and therefore while the suits are in their most moist condition, will be subjected to a greater degree of heat than during the latter stages of their travel through the machine.

With these general objects in view, and others that will appear as the nature of the improvements is better understood, the invention consists substantially in the novel 45 construction, combination, and arrangement of parts hereinafter fully described, illustrated in the accompanying drawings, and pointed out in the appended claims.

In the drawings, Figure 1 is a side elevation 50 of a drying machine embodying the herein-described invention. Fig. 2 is a plan view thereof, a portion of the top of the machine being removed, and the upper stretch of the conveyer being also broken away. Fig. 3 is

an end elevation viewing the machine from 55 the feed end thereof, the end portion being removed to disclose the interior construction of the machine. Fig. 4 is a detail sectional view of a portion of the conveyer. Fig. 5 is a detail perspective view of one of the at- 60 taching devices for connecting the slats to the conveyer chains, and illustrating the manner of such connection. Fig. 6 is a detail fragmentary elevation illustrating the clutch employed in connection with the driv- 65 ing mechanism for the conveyer.

Referring in detail to the drawings, the numeral 1 designates the casing of the herein-described machine, which casing is divided through the medium of a longitudinally-extending partition 2 into a heating chamber 3 and a drying chamber 4. The latter is provided with a slatted floor 5 that is raised sufficiently above the base line of the casing to permit the air in the drying chamber passing from the bottom of the latter into the heating chamber 3, and said chamber 3 is provided with a plurality of heating coils through the medium of which the temperature of the air, as it circulates through the 80 chamber 3, is raised to the required degree. That the heating of the air may be accomplished with the greatest economy, and to enable the suits, at the initial stage of transit through the machine, being subjected to a 85 greater degree of heat than during the later stages of such transit, the heating coils are arranged preferably in primary and secondary sets 6 and 7, respectively, the primary coils 6 being divided into upper and lower 90 banks 8 and 9, while the secondary coils are grouped in a single bank, which latter, however, preferably comprises a larger number than either of the banks of the primary set, but not as great as the combined number of 95 coils in the two banks of the primary set. The sets of coils 6 and 7 are merely shown in conventional form, the arrangement described being perfectly obvious to those skilled in the art. It will thus be seen that 100 there is greater radiation in the primary set of coils than in the secondary set, and in view of the fact that the bathing suits have their greatest degree of moisture in passing the primary coils, it is manifest that through the 105 drying action of said coils the suits will not require as high a degree of heat when passing the secondary coils, so that the machine will

be operated much more economically than were the respective sets of coils capable of giving off the same amount of radiation.

It is preferred that the heating coils shall 5 be fed with steam, and to this end a steam main 10 is employed. This latter is provided with a dependent branch 11 controlled by a suitable valve 12, which branch supplied the 10 upper and lower banks 8 and 9 with the necessary steam, and these banks are in turn tapped by a drip pipe 13 to take off the water of condensation. A branch 14 also leads from the main 10, which branch connects with the secondary coils 7, the branch being 15 controlled by a suitable valve 15, and these secondary coils are likewise tapped by a drip pipe 16 for letting off the water of condensation therefrom.

It is, of course, necessary that the air shall 20 be circulated from the heating chamber 3 to the drying chamber 4, and to the accomplishment of this end the partition 2 is pierced at suitable points throughout its length, and preferably adjacent to the upper edge thereof, with a series of openings 17, each of said openings having inserted therein a fan 18, which fans are carried by suitable shafts 19, and said fans are arranged to blow into the drying chamber 4, thus creating a suction 25 within the heating chamber 3, whereby the air is drawn from the bottom of the drying chamber 4, through the slatted floor thereof, into the heating chamber, and over the heating coils, whence the air is forced through the 30 openings 17 and upon the bathing suits in the drying chamber, as will presently appear. In this connection it is to be observed that the ends of the shafts 19 are journaled in suitable bearings 20, which bearings are 35 arranged at the exterior of the casing 1, and by this arrangement it is obvious that the bearings are not subjected to the high temperature of the air within the casing, and hence liability of fire is reduced to a minimum. The bearings for the ends of the 40 shafts that project through the heating chamber are carried by the outer wall of that chamber, as clearly seen in Figs. 1 and 2, and in order that the bearings at the other ends of 45 said shafts may be at the exterior of the casing, as described, the roof of the casing 1 adjacent to the partition 2 is provided with an inclined deck 21, as clearly seen in Fig. 3, which deck also serves the purpose of a deflector for directing the blast from the fans 18 in a downwardly direction upon the suits 50 in the drying chamber 4.

An exhaust fan 22 is also provided to draw out a sufficient quantity of the moist air from 60 the casing 1, and to thereby prevent the hot air within the casing from becoming too saturated with moisture, and the size of this fan is proportioned to the size of the fans 18 for accomplishing this purpose without interfering 65 with the proper circulation of the hot air

within the casing. The fan 22 is carried by a shaft 23 that is mounted in suitable bearings 24, and these bearings are likewise arranged at the exterior of the casing 1.

For driving the respective fans a suitable 70 motor 25 is employed, said motor being preferably mounted upon the casing 1 and belted to a jack shaft 26 mounted at a point upon the casing 1 intermediate the motor 25 and the shaft of the fan 18 that is most remote 75 from said motor. The jack shaft 26 is, in turn, belted to the shaft of the fan just referred to, and the shaft of each of the fans 18 is provided with a pair of pulleys 27 through the medium of which the shafts of all of the 80 fans 18 are belted in series, and simultaneously operated from the jack shaft 26.

For causing the bathing suits to travel through the drying chamber 4 said chamber is provided with an endless conveyer 28. 85 This conveyer comprises a plurality of sprocket chains 29 to which are connected a multiplicity of transversely-extending slats 30. These slats are preferably in the form of angle-irons, and each of the latter is provided at its ends with attaching clips 31 through the medium of which the respective slats are held in engagement with certain links of the sprocket chains 29. The chains 29 travel over a series of sprocket wheels 32 90 arranged at the front and rear ends of the machine, and said wheels are journaled in proximity to an entrance opening 33 and an exit opening 34 arranged, respectively, in the front and rear ends of the machine. At 95 the upper rear portion of the casing 1 are also arranged sprocket wheels 34' over which the chains 29 also pass, and from which sprocket wheels the chains 29 are directed to the forward end of the machine, at which point they pass over additional sprocket wheels 35. The wheels 35 are journaled in the upper portion of a supporting frame 36, and project in advance of the entrance opening 33 of the casing 1 in order that the return 100 stretch of the conveyer will overhang the forward end of the casing. The sprocket wheels 35 are carried by a transversely-extending shaft 37, and upon one end of said shaft is mounted a sprocket wheel 38 over 105 which passes a drive chain 39 that in turn passes over a sprocket wheel 40 carried by a counter-shaft 41 that is journaled upon the forward end of the casing 1, preferably at the side thereof wherein the heating chamber 3 110 is located. This shaft 41 has mounted thereon a worm wheel 42 engaged by a worm 43 carried by a vertically-disposed shaft 44, and the upper end of said shaft 44 engages, through the medium of suitable worm gearing 45, a counter-shaft 46 upon which is mounted a cone pulley 47. The pulley 47 is alined with a reversely-arranged cone pulley 48 that is mounted upon the extremity 115 of the jack shaft 26, and belted thereto in 120 125 130

order that the shaft 46 may be operated by the jack shaft 26. It is sometimes desirable that the travel of the conveyer 28 may be stopped while the fans 18 continue to operate, and to this end a clutch 49 is provided in conjunction with the worm 43, which clutch is operated from a suitable lever 50 connected to the clutch 49 through the medium of a link 51 and a second lever 51'.

10 To support the bathing suits upon the conveyer 28 each of the slats 30 is provided at spaced intervals with L-shaped hooks 52. These hooks are preferably riveted to the vertical flanges of the angular slats, and the 15 free ends of the hooks are projected in the direction of movement of the conveyer. Consequently, when the conveyer is moving through the drying chamber 4 the hooks 52 are at the lower stretch of the conveyer, and 20 the bathing suits are suspended from the hooks by suitable forms or hangers, thus permitting the air to freely circulate between the suits. By reason of the location of the sprocket wheels 34' and 35 it will be seen 25 that the upper or return stretch of the conveyer passes over the top of the casing 1, and consequently as the slats 30 turn upon the wheels 32 and rise to the wheels 34 the hooks 52 are turned in an upward direction, 30 and when the same reach the upper stretch of the conveyer their position is completely reversed to that occupied during the passage through the drying chamber 4. In this position of the hooks it is manifest that the 35 hangers or forms upon which the bathing suits are suspended will follow the respective hooks to the upper or return stretch of the conveyer, but in passing the wheels 32 the suits fold against the slats of the conveyer 40 and lie upon the latter until they reach the sprocket wheels 35. At this point the position of the hooks 52 is again reversed, and as the suits pass over the end of the conveyer, or the terminal of the upper or return stretch 45 thereof, the forms or hangers become automatically released from the hooks 52, and the dry suits leave the conveyer. A chute 53 is carried by the supporting frame 36 immediately beneath the terminal of the return 50 stretch of the conveyer, and as the suits fall from the latter they are received by said chute by which they are directed into suitable receptacles placed at the lower end of the chute.

55 By reason of the construction just described it is evident that the only attendants necessary for the successful operation of the machine are those required for hanging the suits upon the hooks of the conveyer as they 60 enter the drying chamber, the machine automatically handling the suits thereafter and discharging the same as described without further attendants or manual effort.

Suitable pipes 54 provided with sprinkler 65 heads 55 are arranged at different points in

the heating and drying chambers 3 and 4, which pipes are designed to discharge a fire-extinguishing agent in the event that fire should occur within the casing 1, the sprinkler heads 55 serving to automatically discharge the extinguishing agent in a well-known manner when the temperature of the interior of the casing reaches the necessary degree. As a further protection the casing 1 may also be lined with galvanized sheet 75 iron or other suitable material and asbestos.

In the operation of the herein-described machine steam is admitted to the heating coils in the usual manner, and the motor 25 being set in operation it will be seen that the 80 fans 18 cause the air to circulate from the heating chamber 3 into and through the drying chamber 4, and back to the heating chamber 3, a portion of the moist air being removed from the casing by the exhaust fan 85 22. The conveyer 28 being also operated under the influence of the motor 25 the same passes through the drying chamber 4, the wet suits being connected to the conveyer in the manner described, and traversing the 90 length of the drying chamber, whence they emerge at the rear end of the casing and are raised by the conveyer to the top of the machine, following the conveyer back to the feed end of the machine, at which point they 95 are automatically discharged from the conveyer when the terminal of the return stretch thereof is reached, as also previously described.

If at any time it is desired to stop the 100 movement of the conveyer without stopping the operation of the fans, the clutch 49 is suitably manipulated to disengage the conveyer from the vertical shaft 44, and obviously the conveyer is brought to rest. The 105 primary heating coils, being arranged in upper and lower banks, cause the suits to be subjected to the highest degree of heat at the initial stage of their transit through the drying chamber, and when the suits emerge at 110 the rear end of the casing the same have been dried to the necessary extent.

If desired, the casing 1 may be provided with a hood 54', shown by dotted lines in Fig. 1, which hood extends from the rear end of 115 the machine and over the top of the casing to point adjacent or beyond the feed end of the machine. This hood will cause any heat escaping from the rear end of the machine at the point where the dry suits emerge, to follow the return stretch of the conveyer, and thus subject the suits to this heat until the suits have left the conveyer. This hood is not essential, but may be employed in order to further economize in the use of the heat.

The heating chamber 3 may also be provided with suitable openings at different points to enable access being had to the interior thereof, and the drying chamber may also be provided with longitudinally-extend-

ing supporting guides 56 for suspending the weight of the lower stretch of the conveyer as it passes through the machine with the bathing suits attached thereto.

5 While the form of the invention herein shown and described is believed to be a preferable embodiment thereof, it is perfectly obvious that the same is susceptible of various changes in the form, proportion, and 10 minor details of construction, and the right is accordingly reserved to modify or vary the invention as falls within the spirit and scope thereof.

Having thus described the invention, what 15 is claimed as new, and desired to be secured by Letters Patent, is:

1. In a machine of the class described, the combination with a casing, of a conveyer arranged to travel therethrough, means for 20 actuating said conveyer, and means carried by the conveyer for supporting thereon the articles to be dried and to retain the articles upon the conveyer over the return stretch thereof, said means serving to automatically 25 discharge the articles from the conveyer when the terminal of the return stretch of the conveyer is reached.

2. In a machine of the class described, the combination with a casing, of a conveyer arranged to travel therethrough, means for actuating said conveyer, means for circulating the air within said casing, and means carried by the conveyer for supporting thereon the articles to be dried and to retain the articles 35 upon the conveyer over the return stretch thereof, said means serving to automatically discharge the articles from the conveyer when the terminal of the return stretch of the conveyer is reached.

40 3. In a machine of the class described, the combination with a casing, of a conveyer arranged to travel therethrough, means for actuating said conveyer, means for heating the air within the casing, means for circulating the air within said casing, and means carried by the conveyer for supporting thereon the articles to be dried and to retain the articles upon the conveyer over the return stretch thereof, said means serving to automatically 45 discharge the articles from the conveyer when the terminal of the return stretch of the conveyer is reached.

4. In a machine of the class described, the combination with a casing having heating and drying chambers, of a conveyer arranged to travel through said drying chamber, means for actuating said conveyer, and means carried by the conveyer for supporting thereon the articles to be dried and to retain the 55 articles upon the conveyer over the return stretch thereof, said means serving to automatically discharge the articles from the conveyer when the terminal of the return stretch of the conveyer is reached.

60 5. In a machine of the class described, the

combination with a casing having heating and drying chambers, of a conveyer arranged to travel through said drying chamber, means for actuating said conveyer, means for circulating the air within said casing, and 70 means carried by the conveyer for supporting thereon the articles to be dried and to retain the articles upon the conveyer over the return stretch thereof, said means serving to automatically discharge the articles from the 75 conveyer when the terminal of the return stretch of the conveyer is reached.

6. In a machine of the class described, the combination with a casing having heating and drying chambers, of a conveyer arranged to travel through said drying chamber, means for actuating said conveyer, means in the heating chamber for heating the air in its 80 passage therethrough, means for circulating the air through the heating and drying chambers, and means carried by the conveyer for supporting thereon the articles to be dried and to retain the articles upon the conveyer over the return stretch thereof, said means serving to automatically discharge the articles from the conveyer when the terminal of the 85 return stretch of the conveyer is reached.

7. In a machine of the class described, the combination with a casing having heating and drying chambers, of a conveyer arranged to travel through said drying chamber, means for actuating said conveyer, means in the heating chamber for heating the air in its 90 passage therethrough, a fan interposed between the heating and drying chambers for circulating the air through said chambers, and means carried by the conveyer for supporting thereon the articles to be dried and to retain the articles upon the conveyer over the return stretch thereof, said means serving to automatically discharge the articles from the conveyer when the terminal of the 95 return stretch of the conveyer is reached.

8. In a machine of the class described, the combination with a casing, of a slatted conveyer arranged to travel therethrough, means for actuating said conveyer, and means carried by the slats of the conveyer for supporting thereon the articles to be dried and to retain the articles upon the slats over the return stretch of the conveyer, said means serving to automatically discharge the articles from the conveyer when the terminal of the return stretch of the conveyer is 100 reached.

9. In a machine of the class described, the combination with a casing, of a slatted conveyer arranged to travel therethrough, means for actuating said conveyer, and hooks carried by the slats of the conveyer for supporting thereon the articles to be dried and to retain the articles upon the conveyer over the return stretch thereof, said hooks serving to automatically discharge the articles from 105

the conveyer when the terminal of the return stretch of the conveyer is reached.

10. In a machine of the class described, the combination with a casing, of a slatted conveyer arranged to travel therethrough, means for actuating said conveyer, and L-shaped hooks carried by the slatted conveyer for supporting thereon the articles to be dried and to retain the articles upon the conveyer over the return stretch thereof, said hooks serving to automatically discharge the articles from the conveyer when the terminal of the return stretch of the conveyer is reached.

15. 11. In a machine of the class described, the combination with a casing, of a conveyer comprising a plurality of chains arranged to travel over said casing, slats suitably connected to said chains to be propelled by the latter through said casing, means carried by the slats for supporting thereon the articles to be dried and to retain the articles upon the slats over the return stretch of the conveyer, said means serving to automatically discharge the articles from the conveyer when the terminal of the return stretch of the conveyer is reached, and means for actuating said conveyer.

12. In a machine of the class described, 30 the combination with a casing, of a conveyer comprising a plurality of chains arranged to travel through said casing, slats suitably connected to said chains to be propelled by the latter through said casing, hooks carried by said slats for supporting thereon the articles to be dried and to retain the articles upon the slats over the return stretch of the conveyer, said hooks serving to automatically discharge the articles from the conveyer when 45 the terminal of the return stretch of the conveyer is reached, and means for actuating said conveyer.

13. In a machine of the class described, the combination with a casing, of an endless 45 conveyer arranged to travel therethrough, said conveyer having its lower stretch projected through the casing, and its return stretch arranged at the exterior of the casing, and means carried by the conveyer for supporting thereon the articles to be dried and to retain the articles upon the conveyer over the return stretch thereof, said means serving to automatically discharge the articles from the conveyer when the terminal of the 50 return stretch of the conveyer is reached.

14. In a machine of the class described, the combination with a casing having feed and exit openings in its ends, of an endless conveyer arranged to travel through said casing, the lower stretch of said conveyer being projected through said openings, and its return stretch arranged at the exterior of the casing, and means carried by the conveyer for supporting thereon the articles to 60 be dried and to retain the articles upon the

conveyer over the return stretch thereof, said means serving to automatically discharge the articles from the conveyer when the terminal of the return stretch of the conveyer is reached. 70

15. In a machine of the class described, the combination with a casing having feed and exit openings in its ends, of an endless conveyer arranged to travel through said casing, the lower stretch of said conveyer 75 being projected through said openings, and its return stretch arranged at the exterior of the casing, and hooks carried by the conveyer for supporting thereon the articles to be dried and to retain the articles upon the 80 conveyer over the return stretch thereof, said hooks serving to automatically discharge the articles from the conveyer when the terminal of the return stretch of the conveyer is reached. 85

16. In a machine of the class described, the combination with a casing, of an endless conveyer arranged to travel therethrough, said conveyer having its lower stretch projected through the casing, and its return 90 stretch arranged at the exterior of the casing, the terminal of the return stretch being projected beyond the casing, and means carried by the conveyer for supporting thereon the articles to be dried and to retain the articles 95 upon the conveyer over the return stretch thereof, said means serving to automatically discharge the articles from the conveyer when the terminal of the return stretch of the conveyer is reached. 100

17. In a machine of the class described, the combination with a casing, of an endless conveyer arranged to travel therethrough, said conveyer having its lower stretch projected through the casing, and its return 105 stretch arranged at the exterior of the casing, the terminal of the return stretch being projected beyond the casing, and hooks carried by the conveyer for supporting thereon the articles to be dried and to retain the articles 110 upon the conveyer over the return stretch thereof, said hooks serving to automatically discharge the articles from the conveyer when the terminal of the return stretch of the conveyer is reached. 115

18. In a machine of the class described, the combination with a casing, of an endless conveyer arranged to travel therethrough, said conveyer having its lower stretch projected through the casing, and its return 120 stretch arranged at the exterior of the casing, the terminal of the return stretch being projected beyond the casing, means carried by the conveyer for supporting thereon the articles to be dried and to retain the articles 125 upon the conveyer over the return stretch thereof, said means serving to automatically discharge the articles from the conveyer when the terminal of the return stretch of the conveyer is reached, and a chute ar- 130

ranged beneath the terminal of the return stretch of the conveyer for receiving the articles as the latter leave the conveyer.

19. In a machine of the class described, 5 the combination with a casing, of an endless conveyer arranged to travel therethrough, said conveyer having its lower stretch projected through the casing, and its return stretch arranged at the exterior of the casing, 10 the terminal of the return stretch being projected beyond the casing, hooks carried by the conveyer for supporting thereon the articles to be dried and to retain the articles upon the conveyer over the return stretch 15 thereof, said hooks serving to automatically discharge the articles from the conveyer when the terminal of the return stretch of the conveyer is reached, and a chute arranged beneath the terminal of the return stretch of 20 the conveyer for receiving the articles as the latter leave the conveyer.

20. In a machine of the class described, the combination with a casing having heating and drying chambers, of a conveyer for 25 carrying the articles to be dried through said drying chamber, means carried by the conveyer for supporting thereon the articles to be dried and to retain the articles upon the conveyer over the return stretch thereof, 30 said means serving to automatically discharge the articles from the conveyer when the terminal of the return stretch of the conveyer is reached, and heating coils located in

sets having different capacities of radiation, whereby the heat to which the articles are 35 subjected is proportioned to the degree of moisture of the articles as the latter are conveyed through the machine.

21. In a machine of the class described, the combination with a casing having heating and drying chambers, of a conveyer for carrying the articles to be dried through said drying chamber, means carried by the conveyer for supporting thereon the articles to be dried and to retain the articles upon 45 the conveyer over the return stretch thereof, said means serving to automatically discharge the articles from the conveyer when the terminal of the return stretch of the conveyer is reached, heating coils located in said 50 heating chamber and arranged in sets having different capacities of radiation, whereby the heat to which the articles are subjected is proportioned to the degree of moisture of the articles as the latter are conveyed 55 through the machine, and means for circulating the air through the heating and drying chambers.

In testimony whereof we affix our signatures, in the presence of two witnesses.
